UNITED STATES PATENT OFFICE.

LEMUEL C. GAY, OF BOLIVAR, TENNESSEE.

LAMP-CHIMNEY HOLDER.

1,331,010.

Specification of Letters Patent.

Patented Feb. 17, 1920.

Application filed April 22, 1919. Serial No. 291,898.

To all whom it may concern:

Be it known that I, LEMUEL C. GAY, a citizen of the United States, residing at Bolivar, in the county of Hardeman and State of Tennessee, have invented certain new and useful Improvements in Lamp-Chimney Holders, of which the following is a specification:

My invention relates to new and useful improvements in lamp chimney holders, and an important object thereof resides in the provision of means whereby the lamp chimney is securely and detachably retained upon the base of a burner.

Another object of my invention resides in the provision of means for preventing the lamp chimney from being tilted upon the base of the burner which action usually causes the lamp chimney to become disengaged with the usual spring fingers provided upon the base of the burner to frictionally engage the chimney.

A still further object of my invention resides in the provision of means for preventing further rotation of the lamp chimney in one direction after said chimney has been placed in a locked position.

A still further object of my invention resides in the provision of a device of the above mentioned character which is strong, durable, inexpensive to manufacture and is efficient in practice.

Other objects and advantages of the invention will become apparent during the course of the following description.

In the accompanying drawings forming a part of the description and wherein like numerals are employed to designate like parts throughout the same.

0 Figure 1 is a front elevation of the invention with a lamp chimney secured thereto.

Fig. 2 is a transverse horizontal section taken on the line 2—2 of Fig. 1.

Fig. 3 is a fragment of a similar structure showing the lamp chimney upon the base but in an unlocked position.

Fig. 4 is a vertical section taken on the line 4—4 of Fig. 2.

Fig. 5 is a horizontal section taken on the line 5—5 of Fig. 4.

Fig. 6 is a fragmentary view of the lamp chimney showing one of the lugs thereon in detail, and

Fig. 7 is a fragmentary view of the base showing a perspective thereof and the means

for detachably locking the chimney upon the base.

In the accompanying drawings, wherein is shown a preferred embodiment of my invention, the numeral 8 designates a chimney of the usual construction, but upon the outer face of the lower portion of the chimney adjacent the lower edge thereof, I provide two pair of oppositely disposed outwardly extending lugs 9, which are preferably formed of glass upon the chimney, but these lugs may be secured to the chimney in any other suitable manner and may be constructed from any desired material.

The base of my holder consists of a disk shaped base 10, which is provided with the usual screw plug 11 and burner 12. The base 10 is provided with two pairs of oppositely disposed upwardly extending fingers 13, which are adapted to frictionally engage with the sides of the lamp chimney when it is placed upon the base. In the present instance, the fingers 13 are formed integral with the base and extend almost directly upwardly of the periphery of the base, but as more clearly shown in Figs. 1, 5, and 7, the lower portion of each finger extends slightly beyond the periphery of the base, for a purpose which will hereinafter appear.

The means I provide for more securely retaining the chimney upon the base than has been experienced heretofore, consists of two pairs of oppositely disposed sockets indicated in general by the numeral 14. As more clearly shown in Figs. 2, 3 and 7, the sockets are arranged adjacent the spring arms so that one spring arm and one socket coöperate to form one portion of the locking means. The sockets 14 are formed preferably integral with the base and are constructed by first bending the material outwardly of the base beyond the periphery thereof, then upwardly to provide an upwardly extending flange 15, which of course is arranged a substantial distance beyond the periphery of the base and also beyond the outer surface of its co-acting spring finger 13. The upper part or free end of each flange 15 is provided with an inturned lip 16, which lip prevents the lamp chimney from tilting on the base 10 by reason of the top of the lugs contacting with the inwardly turned lips 16 of the sockets. By the specific construction of the spring fingers and

the socket as set forth above, it will be clearly understood that the spring fingers are arranged in the path of movement of the lugs 9 on the lamp chimney, when said chimney is rotated upon the base to engage the lugs 9 with the sockets 14. By so arranging the fingers 13 the lamp chimney is prevented from being rotated in one direction after the lugs have been received in the sockets 14, by reason of one end of each lug 9 abutting with the lower portion of the spring finger.

From the above, it will be seen that when it is desired to place the lamp chimney upon the holder or base, the lower portion 15 of the chimney is placed between the free ends of the spring fingers 13, then forced downwardly until the lower ends of the chimney contacts with the base 10. As usual, the spring fingers 13 frictionally engage 20 with the sides of the lamp chimney and aid in retaining the chimney in an upright position. When placing the lower edge of the chimney in contact with the base, the lugs 9 should be positioned between each 25 pair of sockets 14. Then, by simply rotating the lamp chimney so that the lugs 9 thereon travel toward the sockets 14, it will be seen, as in Fig. 2 that the lugs will be snugly engaged in the sockets and one end 30 of each lug will engage one side of one spring finger 13, as more clearly shown in Fig. 3, in order to prevent further rotation of the lamp chimney in one direction when the chimney is locked upon the base. To 35 detach the lamp chimney from the base, the same is simply rotated away from the spring arm 13 and out of the sockets 14 to the position shown in Fig. 3 of the drawings, then the chimney is simply raised up 40 out of contact with the spring fingers 13.

By reason of the spring fingers 13 and the sockets 14 being formed integral with the base, or in other words out of one piece of material, it will be seen that the holder can 45 be effectively constructed at a minimum cost.

The foregoing description and the draw-

ings have reference to what may be considered the preferred, or approved, form of invention. It is to be understood that I may make such changes in construction and arrangement and combination of parts, materials, dimensions, etc., as may prove expedient and fall within the scope of the appended claims.

Having thus fully described my invention, 55 what I claim as new and desire to secure by Letters Patent, is—

1. The combination with a lamp chimney having oppositely disposed lugs on its lower end, of a base, oppositely disposed sockets 60 on said base for the reception of said lugs to lock the chimney upon the base, and an upwardly extending finger on said base arranged adjacent each socket for frictional engagement with said chimney, and said fingers being arranged in the path of movement of said lugs to prevent movement of said lugs in one direction when they are received in said sockets.

2. In a lamp chimney holder, a lamp 70 chimney having oppositely disposed outwardly extending lugs on the lower edge thereof, a base, oppositely disposed upwardly extending flanges on said base and arranged beyond the periphery thereof to 75 receive said lugs, each flange being provided with an inturned lip to prevent upward movement of the lugs with relation to said base when the chimney is locked upon the base a spring finger arranged adjacent each 80 flange and extending upwardly of the periphery of said base to frictionally engage said chimney, and said fingers being arranged in the path of movement of said lugs to prevent movement of the lugs in one direction 85 when they are received in said sockets.

In testimony whereof I affix my signature in presence of two witnesses.

LEMUUEL C. GAY.
